UNITED STATES PATENT OFFICE.

CHARLES F. PIKE, OF PHILADELPHIA, PENNSYLVANIA.

PNEUMATIC-DESPATCH-TUBE SYSTEM.

SPECIFICATION forming part of Letters Patent No. 566,015, dated August 18, 1896.

Application filed May 31, 1895. Serial No. 551,222. (No model.)

To all whom it may concern:

Be it known that I, CHARLES F. PIKE, a citizen of the United States, residing at Philadelphia, in the county of Philadelphia and State 5 of Pennsylvania, have invented certain new and useful Improvements in Pneumatic-Despatch-Tube Systems, of which the following is a specification, reference being had therein to the accompanying drawings.

10 My invention has relation to pneumatic-despatch-tube systems wherein there are a number of stations with inlet and outlet tubes joining the main-line tube and provided with switches, receivers, and transmitters. In 15 pneumatic-despatch-tube systems with central and sub stations as heretofore constructed, the carriers are sent from the main to the substations, the switch-operating mechanism for operating the switches at the sub- 20 stations being located at the central station. Consequently when necessary to send a carrier from one substation to another substation in advance it is necessary to send it to the central station and then from the central 25 station to the advance substation.

The object of my invention is to avoid the double handling of a carrier and insure greater rapidity of despatching by providing each station with switch-operating mechanism 30 by means of which a carrier can be sent from any substation to any advance substation of the line.

A further object of my invention is to prevent collision by giving control of the line to 35 the central station or substation sending the carrier, said control consisting in rendering the remaining substations or central and sub stations inoperative and afterward restoring them to an operative condition by the action 40 of the carrier.

My invention accordingly consists of the constructions, arrangements, and combinations of the parts, as hereinafter shown and described.

45 In the accompanying drawings, Figure 1 is a diagrammatic plan of a pneumatic-despatch-tube system having a central station and substations and mechanism for operating the switches and controlling the line which 50 embodies my improvements. Fig. 2 is a plan of the operating and controlling devices for a

substation in its normal position. Fig. 3 is a similar view showing the device in position to render the substation inoperative. Fig. 4 is a plan of the operating-levers. Fig. 5 is 55 an end view of the same.

In Figs. 1, 2, and 3, A² is the transmitter, provided with the gate a of the outlet-tube A' of the central station E.

b', b², b³, and b⁴ are the operating-levers for 60 setting the switches and rendering the line inoperative and are pivotally mounted on a pin b⁵, which is supported at its ends by the bearings b⁶ and b⁷. (See more plainly Fig. 4.) To the bearing b⁶ is connected a current-wire x. 65 To the levers b', b², and b³ are secured the contact-springs b⁸, b⁹, and b¹⁰ for setting the switches of the different stations by making a circuit when raised against the contacts e', e², and e³, (see more plainly Fig. 5,) which are 70 secured to the bar b¹² by means of the screws b¹³, b¹⁴, and b¹⁵. b⁴ is not provided with a contact-spring, as it is not employed to set a switch. The contacts are insulated and provided with current-wires. 75

b¹⁶ b¹⁶ b¹⁶ are contact-arms formed on the levers b², b³, and b⁴, respectively, and make contact with the contact-plates 4, 5, and 6 to lock or render the system inoperative. The operating-lever b' is not provided with a like 80 contact-arm and contact-plate, as it is not necessary to lock the system when sending a carrier to the first station. The operating-levers b', b², b³, and b⁴ are also provided with the locking-arms b¹⁷, b¹⁷, b¹⁷, and b¹⁷. 85

The mechanism for locking or rendering the line inoperative is composed of the helix c, provided with the core or armature c', its lower end being wide to engage the arms b¹⁷. On its upper end is formed the conical head 90 c² and groove c³. The trip c⁴ holds the armature in its normal position and is withdrawn by the action of the magnet c⁵. The end c⁶ of the bell-crank lever c⁹ rests in the groove c⁸. The bell-crank c⁹ is pivoted at c¹⁰. The 95 pin c¹¹, which is free to slide in the opening a' into the transmitter A², is pivoted to the end c¹² of the bell-crank lever c⁹. When the parts are in the normal position shown in Fig. 2, the operating-levers can be raised to 100 make contact and a carrier can be inserted in the transmitter A². Should the magnet c⁵ be

energized from another station, the trip c^4 will be attracted from the head c^2 of the armature c' , allowing it to drop, its lower end passing down behind the arm b^{17} , which prevents the operating-lever being raised, and at the same time pin c^{11} is caused to enter the transmitter A^2 , acting as an obstruction to prevent a carrier being introduced, as shown in Fig. 3. Thus the station is made inoperative until the helix c is energized to cause the armature c' to return to its normal position.

In Fig. 1 the connection and location of the parts described are shown. It will be observed that the central station E is equipped with the three contacts e' , e^2 , and e^3 , contact-plates 4 and 5, contact-plate 6 being unnecessary, as no carrier would be sent from the transmitting end of the central station to its receiving end through the tube A . At substation E' the contacts e^2 and e^3 and the contact-plates 4, 5, and 6 are used. At substation E^2 contact e^3 and contact-plates 5 and 6 are used. At substation E^3 only contact-plate 6 is necessary. Contact e' is connected to the switch at substation E' by means of the wire 1. All of the contacts e^2 are connected to the switch of substation E^2 by means of the wires 2. All of the contacts e^3 are connected to the switch of substation E^3 by means of the wires 3. When an operating-lever is raised to contact at any station, the switch of the station bearing the same number as that of the contact is opened or set. Any construction of switch may be employed, and as it forms no part of this invention it is not shown. The magnets c^5 of the several stations are connected in the wire 7, which has ground connections at both of its ends. At each station the contact-plates that are numbered 4, 5, or 6, which may be located there, are connected to wire 7 by the wires 9 and 10 and the contact-arms b^{16} to the same wire by means of the wire 8, which is provided with the battery o , the lower end of the arm b^{16} being insulated from the arm itself. When the arm b^{16} is brought into contact with either of the contact-plates 4, 5, or 6 at the main station or substations, all of the magnets c^5 in the system are energized. All of the helices c at the several stations are connected in the wire 11, which has ground connections at both of its ends. In each of the inlet-tubes B of the several stations is located the contact m , which is connected to the wire 11 by means of the wires 12 and 13. In the latter wire is the battery o . When a carrier enters the inlet-tube B and makes contact with m , all of the helices c in the system are energized. There is also in the inlet-tube B a contact n , by means of which the switch of that station is reset or restored to its normal position.

When it is desired to send a carrier from the central or main station E to substation E^3 , the gate a is raised and the carrier inserted beyond the pin c^{11} . The gate is then closed. The operating-lever b^3 is then raised and contact made with the contact e^3 , which,

by means of the wire 3, sets the switch at substation E^3 . At the same operation the contact-arm b^{16} makes contact with contact-plate 5, sending a current through wire 7 to all of the magnets c^5 in the system, causing them to attract their respective trips c^4 , allowing the armature c' to drop, rendering the line inoperative, as before described. When the carrier enters the inlet-tube of substation E^3 , it makes contact with the contact m , energizing all of the helices c in the system, restoring the system to an operative condition. It also notifies the operator of the arrival of the carrier he has sent. The carrier also makes contact at n , resetting the switch.

When a carrier is sent from substation E' to substation E^2 or E^3 , the operation is the same as described, or from substation E^2 to substation E^3 ; but in sending a carrier from substation E^3 to the main or central station E there is no switch to be set and only the line to be locked by contact-plate 6. Thus it is easily to be seen that the switch of a station can be set from any other station in its rear and the system be made inoperative at the same moment of time and remains so until restored by the action of the carrier.

It is obvious that the construction, arrangement, and combination of the parts may be greatly varied without departing from the spirit of my invention.

Having thus described my invention, what I desire to claim and secure by Letters Patent is—

1. In a pneumatic-despatch-tube system having stations with receiving and transmitting branch tubes, switches at the junction of the receiving branch tube and the main-line tube, and a switch-operating mechanism located at each station provided with electric circuit connection for the switches of all advance stations, substantially as set forth.

2. In a pneumatic-despatch-tube system having stations with receiving and transmitting branch tubes, a transmitter for the transmitter-tube, switches at the junction of the receiving branch tube and the main-line tube, switch-operating locking and unlocking mechanism located at each station, the locking mechanism being under the control of the switch-operating mechanism and the unlocking mechanism under the control of an arriving carrier, substantially as set forth.

3. In a pneumatic-despatch-tube system, stations provided with the operating-levers $b^1 b^2 b^3$ and contacts e' , e^2 and e^3 in combination with the circuit-wires 1, 2 and 3 and switches of the advance stations of the system substantially as set forth.

4. In a pneumatic-despatch-tube system, the operating-levers $b^1 b^2 b^3$ contact-plates 4, 5 and 6, provided with circuit-wires in electric circuit with locking mechanism at each station of the system, and contacts in each receiving-tube provided with electric circuit-wires in circuit with the unlocking mechanism at each station in the system, contact be-

ing made by an arriving carrier to establish the circuit to unlock the stations of the system substantially as set forth.

5. In a pneumatic-despatch-tube system, stations having inlet and outlet tubes, transmitters provided with locking mechanism, switches at the junction of the inlet-tube and the main line, operating mechanism for said switches constructed to be locked and un-

locked, in combination with electric circuit connection for the several stations, substantially as set forth.

In testimony whereof I have affixed my signature in presence of two witnesses.

CHARLES F. PIKE.
